[57] **CLAIM**

The ornamental design for a tool for removing arrowheads from trees or the like, as shown and described.

DESCRIPTION

FIG. 1 is a perspective of a tool for removing arrowheads from trees or the like showing my new design; FIG. 2 is a front elevational view thereof, the rear view being a mirror image;

FIG. 3 is a top plan view thereof;

FIG. 4 is a bottom plan view thereof;

FIG. 5 is a left side elevational view thereof; and

FIG. 6 is a right side elevational view thereof.

The broken line showing of the arrowhead is for illustrative purposes only and forms no part of the claimed design.
